UNITED STATES PATENT OFFICE

EDWARD M. NOTHACKER, OF COLUMBUS, OHIO, ASSIGNOR TO THE BUCKEYE STEEL
CASTINGS COMPANY, OF COLUMBUS, OHIO

RAILWAY ROLLING STOCK

Application filed January 4, 1929. Serial No. 330,209.

This invention pertains to railway rolling stock, and more particularly to improvements in car trucks. The invention is directed especially to improving trucks of the "quick 5 wheel change" type.

The main purpose of the invention is to provide a car truck in which the side frames are normally interlocked with the spring plank; said plank being vertically movable 10 relatively to the side frame and being adapted to lift the side frames with the plank after the plank has been elevated to a predetermined extent relatively to the side frames. This invention will facilitate the detachment 15 of the side frames and enable the removal of the wheels to be expedited.

A further object is to furnish side frames of improved form, having overhanging ledges or walls, designed to be engaged by the spring 20 plank to enable the plank while being elevated, to lift the side frames during the course of the elevation, and only after the plank has been raised to a predetermined degree relatively to the side frame.

25 The invention is illustrated in the accompanying drawings, and will now be described with reference thereto.

Referring to the drawings,

Fig. 1 is a side elevation of a car truck 30 provided with my improvements.

Fig. 2 is a top plan view of a portion of the truck, partly in horizontal section; the section being taken on line 2-2 of Fig. 1.

Fig. 3 is a vertical sectional view on line 33 3-3 of Fig. 1, and illustrating the manner of placing blocks between the spring plank and the rails for holding certain of the parts in an elevated position.

Fig. 4 is an enlarged vertical sectional view 40 of a detail on line 4-4 of Fig. 2.

In the drawings, 1 indicates the usual side frames, each of which is provided at its ends with the conventional integral journal boxes 2 to receive the axles (not shown) of the 45 wheels 3. As is customary in structures of this character, the lower bar 4 of the yoke of each side frame is provided (see Fig. 4) with short upwardly extending lugs 5 that engage holes 6 in the spring plank 7 for interlocking 50 the spring plank with the side frames. The

spring plank is preferably provided with integral brackets 8 forming part of the brake rigging.

As is also present practice, the bolster 9 of the truck has its ends resting on springs 10 which in turn are supported by the ends of the spring plank 7.

My invention departs from the ordinary trucks in the following particulars. The columns 11 of each side frame are provided near 60 their lower ends with horizontal grooves 12 located opposite one another, and the upper walls of these grooves are formed by ledges 13 which overhang side flanges or extensions 14 at each end of the spring plank.

The web 15 at the bottom of each side frame is recessed, as shown at 16, and the ends of the spring plank project laterally beyond these recesses, as best shown in Fig. 3.

Assuming therefore, that jacks are placed 70 on the roadway, with their heads occupying the recesses 16, and abutting against the end portions 17 of the spring plank, it will be appreciated that as the heads of the jacks are elevated, the spring plank will be caused to 75 rise, and as it moves upwardly, it will elevate the springs 10 and the bolster 9, until the upper edges of the flanges 14 of the spring plank contact with the ledges 13, and then it is apparent that if the jacks are elevated fur-

ther, the side frames will rise with the spring plank. In this way the side frames may be elevated to a convenient height to permit the wedges and brasses to be readily removed, and obviously, when the side frames have reached this height, the studs 5 will have been disengaged from their holes 6. Now blocks 18, such as shown in Fig. 3, may be introduced between the rails 19 and the spring plank to 80 hold the latter and the parts which it supports, in elevated position while the side frames are easily removed by sliding the same laterally along the upper edges of the spring plank flanges 14.

95 While I have herein shown and particularly described the preferred embodiment of my invention, I do not wish to limit myself to the precise construction and arrangement as herein set forth, but intend to include as my 100

invention, all embodiments falling within the terms of the appended claims.

What I claim and desire to secure by Letters Patent is:

1. A car truck including a side frame member having a bolster opening, a spring plank extending into said opening, resting on and interlocked with the side frame member, said spring plank being vertically movable relatively to the side frame member, abutment surfaces on the side frame member and spring plank, adapted to permit the side frame member to be lifted by the spring plank after the latter has been elevated to a predetermined extent relatively to the side frame member, springs mounted on the spring plank, and a bolster resting on the springs and extending into the bolster opening, the distance between the top of the bolster and the top of the bolster opening being materially greater than the distance between the abutment surfaces on the side frame member and spring plank, whereby when the spring plank is elevated relatively to the side frame, the abutment surfaces on the spring plank will contact with the abutment surfaces on the side frame before the bolster reaches the top of the bolster opening.
2. In a car truck, a side frame member and a spring plank member, the side frame member having a bolster opening into which the spring plank member extends, one of said members having guides and the other having extensions slidable in said guides, means interlocking said members together and permitting disengagement of the members when one member is elevated relatively to the other member, abutment surfaces on the members adapted to engage one another after the spring plank member has been elevated to a predetermined height, and permitting both members to be simultaneously raised after the spring plank member has reached such height, springs mounted on the spring plank, and a bolster extending into the bolster opening and resting on said springs, the distance between the bolster and the top of the bolster opening being materially greater than the distance between the abutment surfaces on the spring plank member and the side frame member.
3. In a car truck of the quick wheel change type, a side frame member having an integral tension member and a bolster opening arranged above the tension member, a spring plank member extending into said opening and resting on said tension member, means forming part of the tension member and spring plank member for interlocking those members together, said means being separable upon movement of the spring plank member upwardly relatively to the side frame member, abutment surfaces on the side frame member and spring plank mem-
- ber designed to impinge against each other after the spring plank member is raised a predetermined distance, after which the spring plank member may lift the side frame member, springs supported by the spring plank, and a bolster resting on the springs and having an end portion projecting into said bolster opening, said end portion being of less width than the upper portion of the bolster opening, whereby the side frame may be removed outwardly when the spring plank is in said elevated position.
4. In a car truck of the quick wheel change type, a side frame member having a bolster opening and an integral tension portion spanning the lower end of said opening, a spring plank member extending into said opening, one of said members having short studs and the other member having apertures to receive said studs for interlocking the spring plank member in engagement with said tension portion, the spring plank member being capable of upward movement relatively to the side frame member for disengaging the studs from the apertures, abutment surfaces on the members adapted to contact after the studs have disengaged the apertures, whereby the spring plank member may be employed to lift the side frame member, springs supported by the spring plank, and a bolster resting on the springs and having an end portion projecting into said bolster opening, said end portion being of less width than the upper portion of the bolster opening, whereby the side frame may be removed outwardly from the spring plank and bolster when the spring plank is in elevated position.
5. In a car truck of the quick wheel change type, a side frame having columns provided with grooves and a tension portion arranged below and forming walls for said grooves, a spring plank extending between said columns, resting on said tension portion and having extensions engaging the grooves, said extensions being of less height than the grooves to permit the spring plank member to be elevated relatively to the side frame, means interlocking the bottom of the spring plank member to said tension portion, abutment surfaces on the spring plank and side frame to permit the side frame and spring plank to be elevated in unison after the spring plank has been raised sufficiently to disengage said interlocking means, springs resting on and elevatable with the spring plank, and a bolster resting on and elevatable with the springs, said bolster being free of outside stops in order to permit outward removal of the side frame when the spring plank, springs and bolster are in elevated position.
6. In a car truck of the quick wheel change type, a side frame member having an opening therein, said side frame having substan-

tially vertical columns provided with grooves having overhanging ledges, the side frame also including an integral tension portion arranged below said grooves and spanning 5 said opening, a spring plank resting on said tension portion and having side extensions projecting into said grooves, said extensions being normally spaced below said ledges, and a stud and aperture connection for interlocking 10 the spring plank to the tension portion.

7. In a car truck of the quick wheel change type, a side frame having substantially vertical columns provided with horizontal grooves forming overhanging ledges, a spring 15 seat integral with said columns, a spring plank having one of its ends extending into said opening resting on the spring seat, and having side extensions projecting into said grooves, said extensions being spaced downwardly from the ledges, and stud and aperture connections between the bottom of the 20 spring plank and the spring seat, each stud being of a height less than the distance between said ledges and the tops of said extensions.

8. In a car truck of the quick wheel change type, a one-piece side frame having substantially vertical columns provided with grooves forming overhanging ledges, a spring plank 30 resting on the tension portion of the side frame and having side flanges located in said grooves and arranged below and spaced from said ledges, stud and aperture connections interlocking the bottom of the spring 35 plank to the tension portion of the side frame, springs resting on the spring plank, and a bolster resting on said springs and projecting outwardly between said columns, the width of the end of the bolster being less than the 40 distance between the upper portions of said columns, whereby the side frame may be freely removed outwardly from the bolster and spring plank when those elements are in elevated position.

45 9. In a car truck, a side frame having an opening, substantially vertical columns forming part of the side frame and provided with grooves forming overhanging ledges, a spring plank having one of its ends extending into the side frame and its sides arranged immediately below and spaced from said ledges, stud and aperture connections between the spring plank and the side frame, the side frame being recessed, and a portion of the 50 spring plank projecting over said recess to permit a jack to engage the under surface of the extremity of the spring plank.

10. In a car truck, a one-piece side frame having an opening therein and a tension portion, a spring plank having one of its ends extending into said opening and resting on said tension portion, overlapping surfaces on the plank and side frame normally spaced apart but adapted to be brought into engagement when the plank is lifted relatively to the

side frame, stud and aperture connections normally interlocking the bottom of the plank to the tension portion of the side frame, but adapted to be disengaged from each other when said overlapping surfaces are brought into engagement, springs resting on said plank, and a bolster end supported by said springs, the bolster end being of less width than the side frame opening, whereby when the spring plank and the parts which it supports are in elevated position, the side frame may be removed outwardly from the bolster and spring plank.

11. A car truck comprising a side frame member having a bolster opening defined by a compression portion, columns and a tension portion, a spring plank extending into said opening, resting on said tension portion and interlocked with the side frame member, said spring plank being vertically movable relatively to the side frame member, abutment surfaces on the side frame member and spring plank, adapted to permit the side frame member to be lifted by the spring plank only after the latter has been elevated 80 to a predetermined extent relatively to the side frame member, springs mounted on the spring plank, and a bolster extending into said opening and resting on the springs, the distance between the top of the bolster and the compression portion of the side frame being materially greater than the distance between the abutment surfaces of the spring plank and the abutment surfaces of the side frame, to permit the spring plank, springs 85 and bolster to be elevated as a unit before said abutment surfaces contact.

12. A car truck comprising a side frame member having a bolster opening defined by a compression portion, columns and a tension portion, a spring plank extending into said opening, resting on said tension portion, and interlocked with the side frame member, said spring plank being vertically movable relatively to the side frame member, abutment surfaces on the side frame member and spring plank, adapted to permit the side frame member to be lifted by the spring plank only after the latter has been elevated to a predetermined extent relatively to the side frame member, springs mounted on the spring plank, and a bolster extending into said opening and resting on the springs, the end portion of the bolster being free of outside stops in order to permit the side frame member to be removed from the spring plank, springs and bolster, after the spring plank, springs and bolster have been elevated, and while the spring plank, springs and bolster are in assembled relation.

In testimony whereof, I have signed this specification.

EDWARD M. NOTHACKER.
